DESIGN FOR A COMBINED HOOD AND CAPE

Mark E. Atwood and Joseph Gordon Atwood,
Wauwatosa, and William L. Armstrong, Milwaukee, Wis.

Application March 2, 1938, Serial No. 75,522

Term of patent 3½ years

To all whom it may concern:

Be it known that we, Mark E. Atwood, Joseph Gordon Atwood, residing at Milwaukee, in the county of Milwaukee and State of Wisconsin, and William L. Armstrong, residing at Milwaukee, in the county of Milwaukee and State of Wisconsin, have invented a new, original, and ornamental Design for a Combined Hood and Cape, of which the following is a specification, reference being had to the accompanying drawing, forming part thereof.

In the drawing:

The dominant or characteristic features of our new design are shown in solid lines.

We claim:

The ornamental design for a combined hood and cape, substantially as shown and described.

MARK E. ATWOOD.
JOSEPH GORDON ATWOOD.
